UNITED STATES PATENT OFFICE.

STANLEY E. ATHERTON, OF CLEVELAND, OHIO.

GRAB BUCKET.

Application filed June 3, 1922. Serial No. 565,642.

To all whom it may concern:

Be it known that I, STANLEY E. ATHERTON, a citizen of the United States, and resident of Cleveland, in the county of Cuyahoga and State of Ohio, have invented certain new and useful Improvements in Grab Buckets, of which I hereby declare the following to be a full, clear, and exact description, such as will enable others skilled in the art to which it appertains to make and use the same.

The objects of the invention are to provide a grab or clam shell bucket of the two line type, one line being employed for holding up the bucket and the other for closing the same. The invention particularly relates to a bucket in which an oscillating lever is secured to a shaft which is positioned above the bucket shaft, and used in connection with the closing rope to give positive closing action and increased closing power in the operation of the scoop members.

The particular objects attained by the construction of this bucket are to locate the sheaves of the lever in such a position that they will not become fouled with the material of the load during the operation of the bucket, and to give more perfect control of the operation thereof and to obtain increased smoothness of action and great power.

Further a noncollapsible form of head is employed which will be comparatively rigid and will retain its shape at all times and under all conditions of use, during the operation of the bucket. In this device the operating connections or hitches are made with the levers and one set of bail arms and the shaft upon which the lever arms, are pivoted is pivoted above the level of the bucket shaft upon upright supports which are in turn pivoted upon the bucket shaft.

The invention includes a pair of scoop members having their inner and upper edges pivoted upon a common bucket shaft, and having bail arms connected to their outer and upper edges, with an elevated head, in spaced positions thereon.

It includes means for giving comparative rigidity to the head to prevent it from collapsing, which preferably includes an extension of one set of bail arms, and link connections between these extensions and the pivotal points of the other set of bail arms in said head.

It includes a rocking lever and upright supporting members mounted on the bucket shaft to which the lever is pivoted, one end of the lever being pivoted upon one set of bail arms and fulcruming thereon, and block 60 and tackle mechanism operatively connected with one end of said lever and with a sheave or point at the upper end of the bucket and preferably adjacent to one end of said head, by means of which the lever is operated. 65

The invention is hereinafter described, exemplified in the accompanying drawings and specifically pointed out in the claims.

In the accompanying drawings Fig. 1 is a side elevation of the bucket showing the 70 scoop members in the open position, Fig. 2 is a similar view showing the scoop members closed, Fig. 3 is an end elevation showing the scoop members in the closed position.

In these views A, A, are the scoop members pivoted together at their upper and inner edges by means of the bucket shaft B.

C, C', C', are pairs of bail arms which are pivotally connected at their lower ends at D, D, with the outer and upper edges of 80 the scoop members, and are connected in spaced positions by means of pins or bolts E, E', with the rigid head F. This head is prevented from tilting in any direction while the bucket is in operation, by means 85 of the extensions G, G, from one set of bail arms and the link or links H, H, pivoted thereto and to the bolt or pin E to which the other set of bail arms is attached.

The extensions G, G, are preferably 90 curved to shorten the links H, H, so as to prevent too much movement of the parts, but this structure while preventing the collapse of the head and its tilting in any direction, does permit a slight yielding movement of the parts, sufficient to prevent them from being torn apart when the scoop members are closing upon the load.

The closing lever is composed of arms J, and K, pivotally mounted upon a shaft L 100 secured intermediate of its ends, in the arms M, M, above the bucket shaft B.

The shaft L is elevated upon the arms M, M, which are pivoted on the bucket shaft.

One arm K of the lever is fulcrumed at N 105 upon one set of bail arms and the other arm is connected with the closing rope through any suitable intervening power increasing block and tackle mechanism.

In Fig. 2 the closing rope I after passing 110

over an idler O pivoted at one side of the head F (and the pivotal point may be on the shaft E of the link C) passes over a sheave P pivoted in the arm, and thence passing over a sheave Q in or adjacent to the head is "dead ended" or terminates in the arm at R.

The number of sheaves may be increased and the number of parts of the rope connecting them may be increased to four or five, and the rope may be dead ended in the head or arm as desired, if more power is desired, but the form of lever employed is as powerful as any known, that of a lever 10 of the second class, which operates quickly and powerfully to close the scoop members together. S, is the holding rope.

Having described the invention what I claim as new and desire to secure by Letters 20 Patent is:

1. In a clam shell bucket, the combination with a bucket shaft, of scoop members pivoted thereon at their adjacent inner and upper edges, a head, sets of bail arms connecting the respective outer ends of said scoop members with said head, a pivot shaft secured adjacent to said bucket shaft and above the same, a closing lever pivotally mounted intermediate of its ends upon said 25 pivot shaft, one end of said lever being fulcrumed upon one set of bail arms, and block and tackle mechanism operatively connected with the other end of said lever and with a point in the upper part of said bucket for 30 operating said closing lever.

2. In a clamshell bucket, the combination with a bucket shaft, of scoop members pivoted thereon at their adjacent inner and upper edges, a head, sets of bail arms connecting the respective outer ends of said scoop members with said head, a pivot shaft secured adjacent to said bucket shaft and above the same, a closing lever pivotally mounted intermediate of its ends upon said 40 pivot shaft, one end of said lever being fulcrumed upon one set of bail arms, and block and tackle mechanism operatively connected with the other end of said lever and with a point in the upper part of said bucket for 45 operating said closing lever, and

a separate support pivoted on said bucket shaft on which said pivot shaft is secured.

3. In a clamshell bucket, the combination with a bucket shaft, scoop members pivoted together and to said shaft, and a head and sets of bail arms connecting said scoop members at their outer ends with said head, of a lever of the second class, pivoted above said bucket shaft, supporting arms upon said bucket shaft for said pivot shaft, a fulcrum 55 point for one end of said lever in one set of bail arms, and block and tackle mechanism operatively connecting said lever with a point adjacent to one end of said head.

4. In a clamshell bucket, in combination, 60 a pair of scoop members pivoted together at their inner and upper edges, an elevated head, a set of bail arms pivoted upon the outer ends of said scoop members and secured to said head in spaced positions 70 thereon, one set of bail arms extended above said head, and a link connection between the outer ends of said bail arm extensions and the securing point of the other set of bail arms in said head.

5. In a clamshell bucket, in combination, 75 a pair of scoop members pivoted together at their inner and upper edges, an elevated head, a set of bail arms pivoted upon the outer ends of said scoop members and secured to said head in spaced positions 80 thereon, one set of bail arms extended above said head, and a link connection between the outer ends of said bail arm extensions and the securing points of the other set of 85 bail arms in said head, a transverse shaft positioned in said bucket above the pivotal connecting point of said scoop members, and a lever pivoted on said transverse shaft and fulcrumed upon one set of bail arms, 90 and block and tackle mechanism operatively connecting said lever with the upper part of said bucket.

In testimony whereof, I hereunto set my hand this 31st day of May 1922.

STANLEY E. ATHERTON.

In presence of—

Wm. M. MONROE,
MARGARET C. LOCHER.
